227,516

PORTABLE WATER TEMPERATURE SENSING AND REMOTE READOUT UNIT

Robert F. Turner, El Paso, Tex., assignor to Jetco
Electronic Industries, Inc., El Paso, Tex.

Filed Feb. 4, 1972, Ser. No. 223,805

Term of patent 14 years

Int. Cl. D10—04

U.S. Cl. D52—7 R

FIG. 1

FIG. 2

FIG. 3

FIG. 4

FIG. 5

FIG. 6

FIG. 1 is a front perspective view of a portable water temperature sensing and remote readout unit showing my new design;

FIG. 2 is a front elevational view thereof;

FIG. 3 is a bottom plan view thereof;

FIG. 4 is a right side elevational view thereof;

FIG. 5 is a rear elevational view thereof;

FIG. 6 is a top plan view thereof.

I claim:

The ornamental design for portable water temperature sensing and remote readout unit, substantially as shown.
